UNITED STATES PATENT OFFICE

CARL STILL, OF RECKLINGHAUSEN, GERMANY

COKE OVEN AND DOOR THEREFOR

Application filed October 26, 1926, Serial No. 144,284, and in Germany November 5, 1925.

My invention relates to an improved means in horizontal coke ovens for withdrawing and leading gaseous products of distillation from the interior of the oven outwards, and the main object aimed to is to replace and simplify in a most advantageous manner the means hitherto used therefor.

One essential feature of the invention consists in an arrangement in horizontal coke ovens for withdrawing the gaseous products of distillation directly from the oven charge adjacent to the doors through one or both of the doors which close the ends of the ovens.

An example of a construction according to the invention is represented in the accompanying drawing in which Fig. 1 shows a vertical longitudinal section of the chamber of a horizontal coke oven as a broken-end portion of the length of the chamber, and Fig. 2 is a horizontal section taken along the line 2—2 of Fig. 1.

The coke oven chamber *a* is closed at the end shown by the door *b* and is filled internally up to the level *i* with the coal *c* to be coked. The coke oven door *b* has a hollow space *e* which is bounded towards the side of the chamber by slats *f* arranged like Venetian blinds. In the horizontal direction the slats *f* may extend over the whole width of the door or of the oven chamber, as has been shown by Fig. 2, or only over a part thereof, according to the requirements and the effect which the suction through the door is intended to produce on the working of the oven. In the upright direction the surface taken up by the slats *f* terminates, preferably, at a certain distance below the upper surface *i* of the charge; in the downward direction it can extend to the sole *s* of the chamber or at a certain level above the sole. The hollow space *e* of the door provided behind the slats *f* extends to its lower edge. Where the lower edge of the door rests on the sole *s* of the oven, a passage *h* is provided in the latter which contains a closing valve *m* and terminates in a discharge conduit *k* arranged in the bottom brickwork at a level below the sole *s* of the oven chamber and extending over the whole length of the oven battery. This conduit *k* is connected to a gas suction

apparatus (not shown). In working, after the oven has been emptied of the coke charge of the preceding distillation period, the door *b* is inserted in the usual manner and sealed up, whereupon the oven, after the second door *b* is also inserted, is charged with fresh coal. When the door *b* is inserted, the hollow space *e* of the door is directly connected to the conduit *k* in the simplest possible manner. When the valve *m* is opened, the gaseous products of distillation are immediately led by means of the suction communicated to the conduit *k* from the interior of the charge of coal *c* through the door *b* into the conduit *k*, as illustrated by the arrows shown in Fig. 1. When the charge has been coked, the valve *m* is again closed and the door *b* removed in the usual manner. The passage *h*, which is now open, is preferably covered during the discharge of the coke by a plate placed at the level of the sole of the chamber. (Not shown). This covering would be unnecessary if the valve *m* were so constructed and arranged that in the closed condition it forms a continuation of the sole of the oven chamber. After these preliminary measures the coke *c* can be discharged without hindrance from that side of the oven chamber since the conduit *k* is at a lower level than the sole *s* of the oven chamber *a*.

The arrangement can be employed for one only or for both oven chamber doors. If only one door is provided it is advisable to select that side of the chamber where the coke discharging machine is placed, because then the building and accessibility of the conduit *k* is facilitated and the temporary covering of the passage *h* at the level of the chamber sole during the discharge is unnecessary.

The invention is not restricted to the construction shown in the drawing. More particularly, the lower part of the door may be connected with the conduit *k*, which is placed below the sole *s* of the chamber, by other means than through a passage *h* which in the ordinary position of the door is directly connected to the hollow space *e*. Also, obviously the inner surface of the door may be arranged in other ways in order to provide the necessary free withdrawal open-

ings for the gaseous products of distillation, than by employment of the slats *f*, for example by providing perforated plates, openings in the door lining, and the like.

5. The advantages of the arrangement consist in the extreme simplicity of the construction and in the convenience of carrying out the working. The usual gas collecting apparatus arranged on the top of 10 the oven and the space required therefor are entirely omitted. The bottom conduit, serving to replace these, can be very easily applied, more particularly in existing oven batteries. The connection of the door with 15 the bottom conduit avoids all the obstructions and obstacles for removing, inserting and fastening the doors. Also, the charging, discharging and other operations of the oven are not interfered with by any discharge leads, connections or the like.

20 What I claim is:

1. In a horizontal coke oven having an open end, a door for closing said open end provided with a hollow space having communication 25 with the coking chamber, means located below the level of the sole of said coking chamber for withdrawing the volatile products of distillation from said chamber, and a communicating connection between said hollow space and said means.

2. In a horizontal coke oven having an open end, a door for closing said open end and provided with a hollow space communicating with the coking chamber of the 35 oven, a suction conduit arranged at a level below the sole of said coking chamber, a communicating connection between said suction conduit and the hollow space, together with means for cutting off said communication.

3. In a horizontal coke oven having an open end, a door for closing said end provided with a hollow space communicating with the coking chamber of the oven, said door having an opening in its lower edge, a suction conduit arranged at a level below the sole of the chamber, a passage connecting said conduit and said opening, and a damper arranged in said passage.

4. In a horizontal coke oven having an open end, a door arranged to close said end and provided with a hollow space extending to the bottom of the door, a suction conduit arranged below the level of the sole of the coking chamber, a passage connecting said conduit and said hollow space, a valve for closing said passage, and spaced inclined slats arranged across the inner face of said door and affording communication 55 between the coking chamber and said space but preventing access of coal to said space.

5. An oven door for horizontal coke ovens comprising an outer face portion and an inner foraminous face portion defining with 60 the outer face portion a hollow space adapt-

ed to lead off the volatile products of distillation from the coking chamber of a coke oven, said door having an opening in its lower edge for the discharge of the volatile products of distillation from said space in a downward direction.

6. An oven door for horizontal coke ovens comprising an outer imperforate face portion and an inner face portion composed of spaced inclined slats defining with the outer imperforate face a hollow space adapted to lead off the volatile products of distillation, said door having an opening in its lower edge, and a suction passage in the coke oven communicating with the opening in the lower edge of the door.

7. An oven door for horizontal coke ovens comprising an outer imperforate face portion and an inner face portion composed in part of spaced inclined slats defining with the outer imperforate face a hollow space, said door having an opening in its lower edge arranged when in operative closed position to communicate with a suction passage below the sole of the oven chamber, whereby the volatile products of distillation may be withdrawn from the coking chamber outwardly through said slatted inner face, hollow space and opening in the lower edge of the door, downwardly and outwardly.

8. An oven door for horizontal coke ovens comprising an outer imperforate face portion and an inner face portion defining with the outer imperforate portion, a hollow space, said inner face portion provided with openings producing communication with said space and the coke oven, said door having an opening in its lower edge arranged when in operative closed position to communicate with the suction passage below the sole of the coke oven and a suction passage in the sole of the coke oven, whereby the volatile products of distillation may be withdrawn from the coking chamber outwardly through the openings in the inner face of the door, hollow space and opening in the lower edge of the door downwardly and outwardly.

In testimony whereof I affix my signature.

CARL STILL.
